CLAIM

The ornamental design for a tote bag, as shown and described.

DESCRIPTION

FIG. 1 is a perspective view of a tote bag, showing my new design, in a closed position;

FIG. 2 is a perspective view of the tote bag in an open position;

FIG. 3 is a top view of the tote bag in a closed position;

FIG. 4 is a front view thereof;

FIG. 5 is a rear view thereof;

FIG. 6 is a right side view thereof;

FIG. 7 is a left side view thereof; and,

FIG. 8 is a bottom view thereof.

The surface shading and contour lines shown in the drawings represent the three-dimensional character and contour of the article, and are not intended to illustrate material, surface ornamentation or surface decoration.

The dashed broken lines in the drawings illustrate environment and form no part of the claimed design.
